(57) **CLAIM**

I claim the ornamental design for a driving light assembly, as shown and described.

DESCRIPTION

FIG. 1 is a front, right perspective view of a driving light assembly showing our new design, according to an embodiment;

FIG. 2 is a rear, right perspective view of the driving light assembly;

FIG. 3 is a front plan view of the driving light assembly;

FIG. 4 is a rear plan view of the driving light assembly;

FIG. 5 is a left side plan view of the driving light assembly, the right side plan view of the driving light assembly being a mirror image of the left side plan view;

FIG. 6 is a top plan view of the driving light assembly; and,

FIG. 7 is a bottom plan view of the driving light assembly. The broken lines shown in the drawings illustrate portions of the driving light assembly in which the design is embodied and form no part of the claimed design. The shade lines shown in FIGS. 1-7 illustrate surface shading and not surface ornamentation, color, or material type.

1 Claim, 7 Drawing Sheets
